UNITED STATES PATENT OFFICE.

STEPHEN A. STELLWAGEN, OF MINNEAPOLIS, MINNESOTA, AND GEORGE B. CARTER
AND WILLIAM L. BERTRAM, OF DETROIT, MICHIGAN, ASSIGNORS TO THE FOSTER
STOVE COMPANY, OF IRONTON, OHIO, A CORPORATION OF OHIO.

DESIGN FOR A STOVE.

43,183.

Specification for Design.

Patented Oct. 22, 1912.

Application filed August 19, 1912. Serial No. 715,935. Term of patent 14 years.

To all whom it may concern:

Be it known that we, STEPHEN A. STELLWAGEN, of Minneapolis, Hennepin county, Minnesota, and GEORGE B. CARTER and WILLIAM L. BERTRAM, residing at Detroit, in the county of Wayne and State of Michigan, all citizens of the United States of America, have invented a certain new, original, and ornamental Design for Stoves, of which the following is a specification, reference being had therein to the accompanying drawings, forming part thereof.

Figure 1 is a side elevation, and Fig. 2 is a front elevation of a stove, showing our new design.

We claim:

The ornamental design for a stove, as shown.

STEPHEN A. STELLWAGEN.
GEORGE B. CARTER.
WILLIAM L. BERTRAM.

Witnesses as to Stellwagen:

R. B. HOSTETTER,
BESSIE ALLEN.

Witnesses as to Carter and Bertram:

JAMES P. BARRY,
W. K. FORD.
